ELECTRIC SIGNALING SYSTEM

Samuel R. Durand, Milwaukee, Wis.

Application October 4, 1934, Serial No. 746,827

5 Claims. (Cl. 250—17)

This invention relates in general to signaling systems, and more especially to systems for transmitting signals by means of electromagnetic waves.

5 The invention is especially applicable to high power radio telegraph and other similar transmitting systems in which the usual commercial low frequency alternating current is converted into direct current of substantially constant voltage by electric valves of the Fleming, or other similar two electrode type, and supplied thereby to other electric valves of the audion, or other similar grid controlled type, which operate to produce continuous oscillations of high frequency 10 for the production of electromagnetic waves.

In order to modulate the high frequency oscillations to produce signals it has heretofore been the practice to interrupt the operation of the valve generating the high frequency oscillations 15 by varying the excitation of the grid electrode thereof, or, as an alternative, to interrupt the supply of the direct current to the oscillator, or amplifier, valve by means of an oil or other type of switch. As is known, however, the operation 20 by the first of the two methods has frequently resulted in unstable operation of the oscillator, and that the frequent interruption of such currents, which often exceeds fifty kilowatts, by the second of the two methods rapidly destroys the 25 contacts of the switch, necessitating frequent renewals and consequent interruption of service.

It has now been discovered that the difficulties heretofore experienced in modulating the high frequency oscillations may be entirely avoided by 30 substituting for the valves of the Fleming type three electrode valves of the gaseous type, including such as the multi-anode mercury arc rectifier, and exciting the grid electrodes thereof in such manner as to control, at will, the production, magnitude and duration of the high frequency oscillations.

The novel features which are believed to be characteristic of the invention are pointed out 35 with particularity in the appended claims; the invention itself, however, both as to its arrangement and method of operation, will best be understood by reference to the following description taken in connection with the drawing in which:

50 Fig. 1 illustrates, in diagrammatic fashion, a transmitting system wherein the invention has been embodied; and

55 Fig. 2 illustrates, in graphic fashion, the operating characteristics of a preferred one of the

types of valves suitable for use as the amplifier valve of Fig. 1.

Referring more particularly to the drawing and first to the system shown in Fig. 1, the numeral 1 designates a generator of radio frequency oscillations as comprising a three electrode valve 2 of the high vacuum type having an anode 3, a grid 6, and a cathode 4, which may be heated to incandescence by any suitable source of current, such as the battery 5 as shown. As shown the anode and cathode are connected by an oscillatory circuit containing the inductances 7 and 8, and a source of current 9, which may be a battery as shown, or may be either a direct or alternating current generator. The cathode 4 is 15 also connected externally with the grid 6 through an inductance 10, inductively coupled with the inductance 8. With the anode and grid circuits connected as shown, as soon as current starts to flow in the anode-cathode circuit, a current is 20 built up in the grid-cathode circuit which tends to flow in the opposite direction and the grid will become negatively charged relative to the potential of the cathode. This cuts down the 25 flow of current in the anode-cathode circuit and as the current decreases, the grid loses its negative charge and becomes positively charged relative to the potential of the cathode. The changes 30 are dependent on the natural periods of the two circuits, they may take place with great rapidity, and they may be readily varied to obtain any frequency desired in the inductance 7 by varying the capacity of the adjustable condenser 11.

In order that the stability of the oscillations produced in the inductance 7 may be maintained 35 independent of the constants of the load circuit herein, indicated as an antenna (which they would not be if, as for example, the inductance 7 was included directly in the antenna circuit), a second valve 21 is interposed between the generator 1 and the work circuit, herein shown as comprising an antenna 30 connected through an inductance 25 with ground as at 26. This second valve has a filamentary cathode 22 which may be heated to incandescence by any suitable source 40 of current, such as the battery 20, and is otherwise similar in construction to the valve 2, but is preferably adapted to handle a greater amount 45 of energy and as having the operating characteristics of the 228-A type, indicated in Fig. 2 50 of the drawing.

The valve 21 is indicated as being supplied with high voltage direct current from a valve 40, to be hereinafter described; and as being coupled with the generator 1, and with the work circuit 55

30—25 by the connection of the cathode 22 and grid 23 thereof with the inductance 7 through a biasing battery 24 and an inductance 12 coupled with the inductance 7, and by the connection of the cathode 22 and anode 27 with the inductance 25 through a direct current blocking condenser 28 and an inductance 29 coupled with the inductance 25. The latter circuit may, preferably, include an adjustable condenser 31 connected across the inductance 29 by which the work circuit may be tuned to resonance at the frequency of the oscillations produced in the inductance 7.

Numerous of the well known grid controlled gaseous type valves may be employed for producing and supplying the high voltage direct current to the valve 21. The multi-anode mercury arc rectifier is, however, particularly adaptable for the purpose because of its ability to deliver greater power at a more constant voltage, and because of its infinite life. Accordingly, such a valve is illustrated as comprising a cathode 41 consisting of a pool of mercury, a plurality of anodes 42, 43, 44, 45, 46 and 47, and a plurality of control electrodes 48, 49, 50, 51, 52 and 53 severally associated with the anodes and on which potentials are impressed to control the moments at which the associated anodes will be operable to start carrying current, as will be hereinafter described. It will be understood that such a rectifier is also provided with means for striking an arc and for maintaining such arc as is well known in the rectifying art and, therefore, not shown or discussed herein.

The current from which the high voltage direct current is produced by the valve action of the rectifier is indicated as being derived from a low frequency polyphase alternating current circuit 54 through a transformer 55, having its delta connected primary winding 56 connected with the circuit 54 and the phase sections of its star connected secondary winding 57 severally connected with the anodes 42—47 of the rectifier; and is supplied to the valve 21 through a conductor 58, connected with the cathode 22 of the valve 21 and with the star point connection of the winding 57, and through a conductor 59, connected with the anode 27 of the valve 21 and with the cathode 41 of the rectifier 40. A reactor 60 is also indicated as being included in series connection with the conductor 59 and a condenser 61 connected across the conductors 58 and 59 for smoothing out voltage ripples which might, otherwise, produce a "ruffing" action on the signaling impulses produced in the antenna circuit.

55 A preferred method for exciting the control electrodes 48—53 to control the rectifying action of the valve 40, and to thereby produce the signals, consists in continuously impressing on each such electrode a direct current potential of variable magnitudes and of such sign as to render the control electrodes negative relative to the potential of the cathode 41; and continually superimposing thereon alternating current potentials having a definite phase relation to the alternating current potentials impressed on the anodes 42—47 and of such magnitude as to render the control electrodes positive relative to the potential of the cathode 41 during the periods of signal production. Such alternating current potentials are indicated in the drawing as being derived from the supply circuit 54 through a control transformer 70, having its delta connected primary winding 71 connected with the supply circuit and the star connected phase sections of its secondary winding 72 severally connected with the control

electrodes 48—53 through current limiting resistances 73; and the direct current potentials as being derived from a direct current generator 74, through a voltage divider consisting of a resistor 75 having a terminal thereof connected with the cathode 41 and a rheostat 76 having the contact arm thereof connected with the star point connection of the winding 72. Thus by varying the position of the contact arm 77 on the rheostat 76 the moments at which the control electrodes are made positive, relative to the voltage of the cathode 41, may be varied and the output voltage $Epdc$ of the rectifier regulated. In addition to regulating the effective voltage of the control electrodes 48—53 by varying the effective resistance of the rheostat 76, and for producing the signals, a relay 78 is provided having contacts 79 adapted to short circuit the resistance 75 upon actuation thereof from a low voltage alternating current generator 80, through an insulating transformer 81 and the signaling key 82. Thus upon closure of the signaling key 82 to produce a dot or dash element of a code message, the relay 78 operates to short circuit resistor 75 and thereby reduce the direct current biasing voltage of the electrodes 48—53, which renders the alternating current potential effective at an earlier moment in the voltage cycle of the potential impressed on the anodes 42—47, with resultant increase of the output voltage $Epdc$ to the valve 21; and when the key 82 is released, during a spacing interval in the code, the relay 78 instantly operates to remove the short circuit from about the resistance 75 thereby causing the direct current biasing voltage to be increased with resultant lowering of the $Epdc$ voltage to the valve 21. By choosing values for the direct current voltage of generator 74 and for the resistance 75 it is readily possible to obtain a direct current negative biasing voltage of such value above the output voltage of the transformer 70 as to completely block the rectifying action of the valve and thereby reduce the output voltage $Epdc$ to zero; or such values may be chosen as will merely reduce the direct current output voltage $Epdc$ to a value which will prevent the radiation of radio frequency energy from the antenna circuit during code spacing intervals. This latter method is a feature of the invention and is of very material importance in "keying" radio transmitters as explained hereinafter in connection with Fig. 2 of the drawing. Of course, the same results may be obtained by varying the output voltage of the transformer 70 instead of varying the direct current biasing voltage.

Fig. 2 of the drawing graphically indicates selected operating voltage and current values for a valve having the electrical characteristics of the 228-A type, which has been found to be particularly suitable for the valve 21 in the practice of the present invention. As indicated in the drawing this valve will, at the selected values, operate to deliver energy to the antenna 30 when the anode-cathode circuit thereof is supplied with current I_0 , from the valve 40, at voltages $Epdc$ varying from six thousand to ten thousand volts, against a negative grid biasing voltage $Egdc$ of one thousand volts when modulated by a radio frequency voltage $Egrf$, from the oscillator 1, having a peak value of four hundred volts. The instrumentalities of the oscillator 1 are, therefore, so proportioned as to impress on the grid-cathode circuit of the valve 21 radio frequency voltages $Egrf$ having a peak value of four hundred volts, and the voltage of the generator 74

and the resistor 15 are so proportioned that, during closed circuit periods of the key 82, to produce dot and dash signaling elements of a code message, current I_0 is supplied to the valve 5 21 from the valve 40 at voltage E_{pdC} of ten thousand volts and converted, by the action of the grid-cathode circuit 12, 22, 23, into oscillations, corresponding in frequency to the oscillations produced in the oscillator 1, and supplied, over the anode-cathode circuit 27-22, 10 29 and 28, to the antenna circuit 25, 30, at a voltage as determined by the transformation ratio of the inductively coupled coils 25, 29. Between each such dot and dash impulse the key 15 is restored to its open circuit position which results in the voltage E_{pdC} being reduced to six thousand volts, at which point the current I_0 is reduced to zero by the biasing action of the E_{gdC} voltage, and the valve 21 cuts off. The valve 40 20 then supplies only such direct current as is necessary to maintain the condenser 61 in its then partially charged condition. It is, therefore, apparent that by the simple process of reducing the output voltage of the valve 40 from ten 25 thousand volts to six thousand volts (a reduction of only forty percent) "keying" of the radio transmitter is accomplished.

Although but a single embodiment of the invention has been illustrated and described, it will 30 be apparent to those skilled in the art that various changes and modifications may be made therein to meet different conditions encountered in its use without departing from the spirit of the invention or from the scope of the appended 35 claims.

It is claimed and desired to secure by Letters Patent:

1. In a signal transmitting system, a source 40 of alternating current, means comprising a multi-anode electric valve of the vapor arcing type having connections with said source and operable to convert current supplied therefrom into direct current by way of arcs when sequentially established between said anodes and the cathode thereof, means supplied with said direct current operable to convert the same into electromagnetic waves, and means for controlling the creation and duration of said waves in accordance with signals to be transmitted comprising 45 in combination control electrodes severally associated with said anodes, means for exciting said control electrodes in such sense as to permit the establishment of said arcs at predetermined moments relative to the voltage frequency of 50 said source of alternating current, and means operable in accordance with signals to be transmitted for varying said excitation in such sense as to vary the moments of establishment of said arcs relative to the voltage frequency of said 55 source of alternating current.

2. In a signal transmitting system, a source of 60 alternating current, means comprising a multi-anode electric valve of the vapor arcing type having connections with said source and operable to convert current supplied therefrom into direct current by way of arcs when sequentially established between the said anodes and the cathode thereof, means comprising an electric valve having an anode-cathode circuit supplied with 65 said direct current operable to convert the same into electromagnetic waves, means comprising a grid cathode circuit of the second said valve and an oscillator coupled therewith for determining 70 and controlling the frequency of said waves, and means for controlling the creation and duration 75 of said waves in accordance with signals to be transmitted comprising control electrodes severally associated with said anodes, means for exciting said control electrodes in such sense as to permit the establishment of said arcs at predetermined moments relative to the voltage frequency of said source of alternating current, and means for varying the moments of establishment of said arcs relative to the voltage frequency of said source of alternating current.

3. In a signal transmitting system, a source of 10 alternating current, means comprising a multi-anode electric valve of the vapor arcing type having connections with said source and arranged to convert current supplied therefrom into direct current at voltages above and below a predetermined voltage value by way of arcs when sequentially established between the said anodes and the cathode thereof, means comprising an electric valve having an anode-cathode circuit supplied with said direct current and operable at the voltage thereof above said predetermined value to convert the same into electromagnetic waves, means comprising a grid cathode circuit of the second said valve and a variable frequency oscillator coupled therewith for regulating the frequency of said waves, and means for controlling the creation and duration of said waves in accordance with signals to be transmitted comprising in combination control electrodes severally associated with the anodes of the first 15 said valve, means comprising a source of alternating current and a source of direct current connected with said control electrodes and impressing voltage impulses thereon of such sign and magnitude and during such recurring periods 20 as to permit the establishment of said arcs at such moments relative to the voltage frequency of the first said source of alternating current as to produce the direct current therefrom at a voltage not to exceed said predetermined value, 25 and means comprising a signaling key operable in accordance with signals to be transmitted for varying the potential of said impulses in such sense as to permit the establishment of said arcs at such moments relative to the voltage frequency of the first said source of alternating current as to produce therefrom the direct current 30 at a voltage above the said predetermined value.

4. The combination with an electromagnetic wave transmitting system comprising an antenna system, an oscillating circuit coupled with said antenna system and arranged to create electrical oscillations therein, and means for energizing said circuit comprising a source of alternating current, and an electric valve having anodes 35 and a cathode connected with said circuit and with said source and arranged to convert current supplied from said source into direct current and the supply thereof to said circuit at voltages above and below a predetermined value, of means 40 for controlling the creation and duration of said oscillations in accordance with signals to be transmitted comprising control electrodes severally associated with said anodes, a source of alternating current connected with said control electrodes and continually impressing potential impulses thereon during such moments as to permit said converting operation of said valve, a source of direct current continuously connected 45 with said control electrodes and impressing there-

- on potential of such sign and magnitude as to modulate said impulses in such sense as to cause the production of the first said direct current at voltages below said predetermined value, and
- 5 means operable in accordance with signals to be transmitted for modulating said impulses in such sense as to cause the production of the first said direct current at voltages above said predetermined value.
- 10 5. In a system of the character described, the combination with means for creating electrical oscillations to produce signals, and means for energizing the same comprising a source of alternating current and an electric current converting device having electrodes connected with the first said means and with said source and arranged to convert current supplied from said
- 15 source into direct current and to supply said direct current to the first said means, of means for controlling the creation and duration of said oscillations in accordance with signals to be transmitted comprising a control electrode associated with the first said electrodes, means for continually impressing voltage impulses on said control electrode of such sign and magnitude and during such moments relative to the voltage frequency of said source of alternating current as 10 to cause the production of said direct current at a voltage of predetermined value, and means operable in accordance with signals to be produced for modulating said impulses in such sense as to cause the production of said direct current 15 at a voltage above said predetermined value.

SAMUEL R. DURAND.
